UNITED STATES PATENT OFFICE.

SAMUEL FRIEDLANDER, OF ASTORIA, AND THEODORE GEISMAR, OF JAMAICA, NEW YORK.

SANITARY TELEPHONE MOUTHPIECE.

Application filed April 14, 1927. Serial No. 183,712.

This invention relates to mouthpieces with particular reference to such as are adapted to telephone transmitters.

The mouthpieces of telephones, especially 5 those located in public booths and which are used continuously, present great germ spreaders and collectors, thus menacing the health of the persons using them.

It is therefore the main object of this invention to provide a cap adapted to fit over 10 the mouthpiece of a telephone, whereby the same will be rendered sanitary.

A further aim is to provide a sanitary cap made so as to be readily removable and replaceable so that a fresh cap may be used for 15 each person utilizing the phone.

These and other objects, such as simplicity, low cost of production, etc., are accomplished by the novel design and construction 20 of an integral element, hereinafter described and illustrated in the accompanying drawing, forming an important component of this disclosure, and in which:—

Figure 1 is a fragmentary, front elevational view of a telephonic transmitting instrument, equipped with a sanitary cap made in accordance with this invention, part of the latter being broken away to show the construction.

Figure 2 is a fragmentary, partial longitudinal, partial side elevational view of the same.

In the drawing, the numeral 5 generally designates the body of a conventional telephone to which is pivoted an ordinary trans-

mitting device 6 equipped with the usual mouthpiece 7.

Fitting over the mouthpiece and extending partially therein, is a concave-convex cap 8, made preferably of wax paper, having its 40 edge 9 bent reentrantly and pinched so as to engage the outer edge 10 of the member 7.

Thus the cap is rendered readily removable, so that each individual user may employ a separate cap when telephoning and by 45 so doing, the spreading of disease due to public telephones is reduced to a minimum.

It will be further noted that the cost of such adapters is very little, particularly when taken in the light of comparison with the 50 beneficial results obtained.

As changes in construction can be made within the scope of the invention, it is intended that all matter contained in the foregoing description or shown in the accompanying drawings, shall be interpreted as illustrative and not in a limiting sense.

Having thus described our invention, what we claim as new and desire to secure by Letters Patent, is:—

A sanitary cap for telephone mouthpieces comprising a circular disc of waxed paper presenting an unbroken concave face and having a flanged periphery adapted to engage over the rim of the mouthpiece.

In witness whereof we have affixed our signatures.

SAMUEL FRIEDLANDER.
THEODORE GEISMAR.
